B. J. DOWD.

PLATEN RELEASE MECHANISM.
APPLICATION FILED SEPT. 7, 1918.

1,312,024.

Patented Aug. 5, 1919.

UNITED STATES PATENT OFFICE.

BERNARD J. DOWD, OF HARTFORD, CONNECTICUT, ASSIGNOR TO ROYAL TYPEWRITER COMPANY, INC., OF NEW YORK, N. Y., A CORPORATION OF NEW YORK.

PLATEN-RELEASE MECHANISM.

1,312,024.

Specification of Letters Patent. Patented Aug. 5, 1919.

Application filed September 7, 1918. Serial No. 253,005.

To all whom it may concern:

Be it known that I, BERNARD J. DOWD, a citizen of the United States, and a resident of Hartford, in the county of Hartford and 5 State of Connecticut, have invented certain new and useful Improvements in Platen-Release Mechanism, of which the following is a specification.

The present invention relates generally to typewriting machines and has more particularly reference to spacing mechanism for effecting not only the usual line spacing but what is commonly known as fractional line spacing.

15 In the patent to Hess, No. 1,196,110, there is shown spacing mechanism with a train of connections from the line spacing elements to the platen including two locking members that constitute a so-called fractional spacing mechanism. In that device, one of the locking members is, at all times, movable with the line spacing mechanism and the other member is, at all times, movable with the platen, said other member being adjustable 20 lengthwise to free it from its fellow and means being provided to urge the locking member that is carried by the platen into engagement with the locking member carried by the line spacing mechanism.

25 The particular form in which the invention is here clothed is that disclosed in the patent to Dowd No. 1,247,383, in which the movable locking member is provided with a removable abutment member seated in its 35 face.

The construction of devices of this character is generally such that the locking members are released by an actuating member that extends through the platen shaft and is 40 operated by pressure on a button adjacent the twirler or knob of the platen, the parts being so arranged that the adjustably movable locking member will reengage its fellow when pressure on the button is released and 45 will cause a return movement of said actuating member lengthwise of the platen shaft. Under some conditions, it may be desirable to prevent reengagement of the movable locking member with its fellow and the object of this invention is to provide means whereby this may be effected. The invention 50 therefore consists of the features of construction hereinafter set forth.

In the accompanying drawings:

55 Figure 1 is a view, partly in elevation and

partly in section, of a platen and release mechanism for the platen showing the invention applied thereto in a preferred embodiment, the parts being shown in the position they occupy when the locking members have been prevented from returning into engagement with each other.

Fig. 2 is a view, similar to Fig. 1, with the portion in elevation in that figure omitted, the section through the platen and associated device being taken at an angle to that shown in Fig. 1 and the parts being shown with the locking members in engagement.

Fig. 3 is a sectional view on the line 3—3 of Fig. 1.

The particular construction of platen, fractional spacer and line spacing mechanism with which the invention is here associated is as follows:

5 indicates a platen of conventional type 75 consisting here of a core 6 and a rubber covering 7. One end of the platen is provided with a head 8 having an inwardly extending hollow boss 9 and an outwardly extending hollow boss 10. The head 8 is secured to the 80 platen by means of screws 11, as shown. 12 is the platen shaft here shown as being secured to the platen by means of a set screw 13.

A typical line spacing mechanism and 85 fractional spacer is here shown consisting essentially of two locking members 14 and 15 and a ratchet 16. The locking member 15 is mounted to rotate freely on platen shaft 12, and ratchet 16 is mounted on a hub 17 of 90 the locking member 15 and turns therewith. The locking member 14 is slidably mounted on a hollow boss 10 of head 8 and is connected with the platen so as to turn therewith. In the present instance, the member 95 14 is of a disk-like character, its dimensions or thickness being sufficiently ample, however, to insure its durability and to impart sufficient strength to withstand the stresses to which it is subjected. In the form herein disclosed, the member 14 consists of a hub portion 18 and, preferably, three outwardly extending arms 19. The peripheral surfaces 20 of these arms are slightly inclined inwardly, as shown, and are provided with fine serrations or teeth that engage serrations or teeth oppositely inclined on an annular member 21 of the locking member 15 for the purpose of effecting fractional spacing as described in the Hess Patent, No. 110

100

105

1,196,110. The locking member 14 is mounted to rotate with the platen and is normally urged into engagement with the locking member 15 by suitable means, which, in the present instance, take the following form: 5 22 indicate pins, suitably secured to the arms of the locking member 14 and having extensions 23 that fit snugly in, and pass through, openings 24 in head 8 and into sockets 25 of the platen. 26 indicates a spring seated between the inner end of socket 25 and a collar 27 that is carried by extension 23. The collar 27 is situated part way down the extension 23 so that the end of the latter projects inside spring 26. The connection just described constitutes, in effect, spring-pressed plungers that normally urge the locking member 14 into engagement with the locking member 15 and, at the same time, insure the rotation, in unison, of the locking member 14 and the platen.

The locking member 14 is provided with an inwardly projecting tongue 33 that extends through an open channel 34 of the hollow boss 10 and into a channel 35 of platen shaft 12. Suitable actuating means, here shown as a rod 36, extends through the channel in platen shaft 12 and is operated from its end by means of a push button 37.

30 As is customary in devices of this character, the platen shaft 12 is provided with a suitable knob or twirler 38, the bushing 39 of which overhangs the end of the platen shaft and is secured to said platen shaft by means, 35 for instance, such as set screw 40. The outer end of bushing 39 is here slightly enlarged, interiorly, as at 41 to afford space for a stop member 42 carried by actuating member 36 provided with a push button 37. The 40 inward movement of this push button is limited by stop member 42 coming in contact with the end of platen shaft 12 and its outward movement is limited by a set screw 43.

45 The actuating member or rod 36 extends through platen shaft 12 and is in abutting engagement with locking member 14 mounted to slide lengthwise of the platen shaft. It will be understood that, when push button 37 is moved inwardly, locking members 50 14 and 15 will be released, thereby admitting of the independent rotation of platen 5 with respect to the line spacing mechanism; and also that when pressure is released from 55 push button 37, spring 26 will urge movable locking member 14 into reengagement with member 15 and will also move the actuating member or rod 36 outwardly and restore it to the position it occupied before it was 60 moved by the operator. In certain eventualities, it may be desired to maintain locking members 14 and 15 in their releasing position and to prevent spring 26 from restoring them into engagement with each other. 65 In order to accomplish this, suitable com-

plementary means are provided on the actuating member and the platen shaft that are relatively adjustable with respect to each other so that, at the will of the operator, the return movement of locking member 14 and actuating member 36 may be prevented. In the particular form these means here take, they consist of a pin 45 carried by actuating member 36 and an arcuate slot 46 formed in bushing 39 of twirler 38 and therefore fast with the platen shaft, said slot having a restricted opening 47 through which pin 45 may enter the arcuate slot 46. The complementary means just described are rotatably adjustable with respect to each other so that pin 45 may be positioned in or out of alignment with restricted opening 47. In the present instance, actuating member 36 is capable of a rotating adjustment around its own axis. It will, 85 therefore, be understood that when pin 45 is in alignment with the restricted opening 46, push button 37 may be pressed inwardly thereby causing locking member 14 to be released from member 15. If it is now desired to maintain the parts in this position, 90 actuating member 36 is given a turn, slight, but sufficient to bring the pin 45 out of alignment with the restricted opening 47. It will be understood that in these circumstances, it is not possible for spring 26 to restore locking members 14 and 15 to their position in engagement with each other. If it is now desired to have the locking members 95 reengage, pin 45 is turned so as to register with the restricted opening 47 when spring 26 will move it outwardly, thus, at the same time, causing 14 to enter firmly into engagement with member 15. It will also be understood that pin 45 may be used to prevent inward movement of push button 37. This can be done by turning actuating member 36 until pin 45 occupies a position such as is shown in Fig. 2 when inward movement of said pin through the restricted opening 47 will 100 be prevented.

I claim:

1. A platen shaft, an actuating member for releasing line spacing mechanism rotatable on its own axis and extending longitudinally of the platen shaft and movable lengthwise thereof, and complementary means on said actuating member and said shaft for preventing or admitting at the will of the operator of lengthwise movement of the actuating member including an arcuate slot near the outer end of the platen shaft having a restricted opening extending from said slot to the outer end of the platen shaft, and a pin rotatable and lengthwise movable with said member which when positioned circumferentially in line with the slot is movable from a point outside of the shaft through said opening into the slot and vice versa. 115 120 125 130

2. Platen release mechanism comprising: a platen and platen shaft, line spacing mechanism for said platen including locking members, means normally urging the locking members into engagement, and means extending through the platen shaft and shafting a lengthwise movement for effecting release of the locking members and a rotary movement at two points for preventing, at the will of the operator, lengthwise movement of the means extending through the platen shaft when the locking members are in either locked or released position. 10
- 5 Signed at Hartford, in the county of Hartford and State of Conn., this 4th day 15 of September 1918.

BERNARD J. DOWD.
